CLAIM

The ornamental design for therapy eye mask, as shown and described.

DESCRIPTION

FIG. 1 is a perspective view of a therapy eye-mask showing our design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof; and,

FIG. 8 is a perspective view thereof shown worn on person's head.

The broken lines showing of a person's head are included for environment and form no part of the claimed design.

1 Claim, 7 Drawing Sheets
